US0D1109672S

(12) **United States Design Patent** (10) **Patent No.:** **US D1,109,672 S**
(45) **Date of Patent:** **** Jan. 20, 2026**

(54) **UNCREWED AERIAL VEHICLE**

(71) Applicant: **Wing Aviation LLC**, Palo Alto, CA (US)

(72) Inventors: **André Peter Prager**, Sunnyvale, CA (US); **Elizabeth Chase Marshman**, San Francisco, CA (US); **Giulia Bissinger Pantalone**, Redwood City, CA (US); **Adem Eminoglu Rudin**, Santa Clara, CA (US); **Jesse Hayden Blake**, Palo Alto, CA (US); **Luis Carlos Prado Cartaya**, San Francisco, CA (US); **Robert William Parks**, Olympia, WA (US)

(73) Assignee: **Wing Aviation LLC**, Palo Alto, CA (US)

(**) Term: **15 Years**

(21) Appl. No.: **29/950,034**

(22) Filed: **Jun. 29, 2024**

(51) LOC (15) Cl. **12-07**

(52) U.S. Cl. **USPC .....** **D12/326**

(58) **Field of Classification Search**

USPC ....., D12/1, 2, 3, 4, 16.1, 319, 320, 321, 323, D12/324, 325, 326, 327, 328, 29, 330, D12/331, 332, 333, 334, 335, 336, 337, D12/338, 339, 340, 41, 342, 343, 344, D12/345; D21/436, 440, 441, 442, 446, D21/447, 448, 449, 450, 451, 452, 453

(57) **CLAIM**

The ornamental design for an uncrewed aerial vehicle as shown and described.

DESCRIPTION

FIG. 1 is of a top perspective view of an uncrewed aerial vehicle showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings depict portions of the uncrewed aerial vehicle that form no part of the claimed design.

1 Claim, 6 Drawing Sheets
